Primary Examiner — Selina Sikder(74) *Attorney, Agent, or Firm* — Lerner, David, Littleneberg, Krumholz & Mentlik, LLP(57) **CLAIM**

The ornamental design for a wafer carrier having pockets, as shown and described.

DESCRIPTION

FIG. 1 is a top perspective view of a wafer carrier having pockets showing our new design;

FIG. 2 is an enlarged view of a portion of FIG. 1;

FIG. 3 is a top plan view thereof;

FIG. 4 is a bottom perspective view thereof;

FIG. 5 is a bottom plan view thereof;

FIG. 6 is an enlarged view of a portion of FIG. 4; and,

FIG. 7 is a right side view thereof, the left side, front, and rear views being the same as the right side view.

The broken lines in the drawings are for illustrative purposes only and form no part of the claimed design.

The dash-dot broken lines define the area corresponding to the enlarged portion shown in FIGS. 2 and 6 and form no part of the claimed design.
